UNITED STATES PATENT OFFICE.

EMILE MOONEN AND ALBERT DUMAIRE, OF PARIS, FRANCE.

SPARKING PLUG.

No. 892,285.

Specification of Letters Patent.

Patented June 30, 1908.

Application filed December 7, 1906. Serial No. 346,763.

To all whom it may concern:

Be it known that we, EMILE MOONEN, engineer, a citizen of the French Republic, residing 33 Rue Dautancourt, Paris, in the 5 Republic of France, and ALBERT DUMAIRE, engineer, a citizen of the French Republic, residing 64 Rue Lamark, Paris, France, have invented certain new and useful Improvements in and Relating to Sparking Plugs, of 10 which the following is a specification.

This invention relates to improvements in 15 sparking plugs for explosion motors, by means of which it is possible to adjust the distance between the spark producing surfaces without it being necessary, as in most known systems, to displace longitudinally the central rod, thus partly dismounting the 20 plug.

One object of the invention is to produce 25 a plug having large surfaces between the sparking parts, thus diminishing the wear of said surfaces and lengthening the life of the plug.

Another object of the invention is to arrange 30 the parts forming the electrodes completely outside of the body of the plug, in order to render them accessible for cleaning purposes, the cleaning being effected by rubbing the parts with a piece of folded emery paper or cloth.

The invention is characterized by the fact 35 that the head terminating the central rod, is provided with plane surfaces, so that the distance relatively to the corresponding surfaces of the other pole of the plug can be adjusted by a simple movement of rotation on the central rod. This arrangement is also intended to facilitate the cleaning.

In the accompanying drawing: Figure 1 40 represents a vertical section through the axis of the sparking plug. Fig. 2 is an external elevation of the same. Fig. 3 is a plan view, and Fig. 4 illustrates a structure of the operative extremity of the plug in 45 which the sparking surfaces are cross-shaped.

The insulating body *a* formed of porcelain, steatite, or other appropriate substance is lodged in the metal body *b*, the screw threaded end *c* of which is screwed on to the 50 motor and is prolonged by a slotted or recessed tubular portion in such a manner as to present four surfaces *d e f g*. The tightening nut *h* and a packing *i* serve to fix the insulating body *a* within the metal body *b* with 55 a tight joint. The central rod *j* of the plug terminates at its lower part in a rectangular

head *k*, which enters the slot or recess in the lower tubular part of the body with a certain amount of play. The upper part *l* of the rod *j* is screw threaded; it receives the tightening nut *m* which serves to fix it in the insulating body *a*. The washer *n* formed of elastic material, compensates for the expansion of the rod *j* and tends to cause it to bear continuously upon the packing *o* which bears 60 against the shoulder *g* on the rod *j*, in such a manner as to form a sufficiently tight joint. The screw threaded extremity *l* likewise receives the milled knob *p* serving as a terminal for the electric conductor. An inner chamfer is provided in order to obviate fouling. 65

The operation is as follows: The body of the plug is attached to the motor in the usual manner, and the central rod *j* is connected to the current conductor. The current traverses this central rod, and sparking takes 70 place in the free spaces existing between the head *k* in which the rod *j* terminates, and the parts *d* and *g* of the slotted lower tubular portion of the metallic part of the plug, for example, between *d* and *2* or between *g* and *3*. 75

In the event of one of the spaces from *d* to 80 2 or from *g* to 3 becoming excessive a repair may be readily effected without dismounting the parts and without the employment of any special tool, by inserting, for example, a knife-blade or screw-driver in one of the recesses 85 1 or 4, and turning the head *k* a sufficient distance to suitably separate the parts 2 and *d*, and *g* and 3. 90

Fig. 4 shows a construction of the lower part of the sparking surfaces in which the central rod *j* is ended by a cross-shaped head *s* and the lower tubular part of the metal body comprises four right-angled slots or recesses which form the four portions *t*. The 95 sparks therefore pass at the four arms of the cross. The head *k* in which the central rod *j* ends may be fitted to this rod as here shown, so as to turn thereon, or may form one with it. 100

The sparking plug is applicable to all explosion motors ignited by means of electric sparks, and in particular to those comprising magnetic ignition.

Having now particularly described and ascertained the nature of our said invention, and in what manner the same is to be performed, we declare that what we claim is:

1. An electric sparking plug for explosion motors, having a body provided with a slotted tubular extension forming one of the poles and a central rod having a head and forming 110

the other pole, the head being provided with a plane surface received by the said tubular extension and rotatable on the central rod for adjusting the distance of the spark producing surfaces.

5. An electric sparking plug for explosion motors, comprising a metal body adapted to be secured to the motor and having a slotted inner end, an insulating body having a longitudinal bore and secured in the metal body, and a rod secured in the insulating body and having a head at its inner end in the slot of the metal body, the outer end of the rod extending beyond the outer end of the said insulating body.

10. An electric sparking plug for explosion motors, comprising a metal body provided with a reduced and screw threaded end forming a slotted extension, an insulating body having a longitudinal bore and secured in the metal body with its outer end projecting beyond the end of the same, a rod in the bore of the insulating body, means for securing the rod in said body, and a movable head

15. on the inner end of the rod in the slot of the metal body.

4. An electric sparking plug for explosion motors, comprising a metal body having a slotted inner end, an insulating body having a longitudinal bore and secured in the metal body with its end projecting beyond the same, a rod in the bore of the insulating body and having its outer end screw threaded and projecting through said insulating body, and provided with a shoulder adjacent to its inner end, a nut on the screw threaded end of the rod, by means of which and the shoulder, the rod is secured in the body, and a head on the inner end of the rod in the slot of the metal body.

20. In testimony whereof we have hereunto set our hands this sixteenth day of November 1906, in the presence of two witnesses.

EMILE MOONEN.
ALBERT DUMAIRE.
